UNITED STATES PATENT OFFICE

2,649,962

AERATOR

Richard Ruemelin, Milwaukee, Wis.

Application January 14, 1949, Serial No. 70,969.

1 Claim. (Cl. 209—136)

1
This invention relates to improvements in aerators.

It is common practice, in sand blasting, to use a sand blast room within which the casting to be cleaned or other article to be blasted is located. The operator usually stands outside of the sand blast room and projects the sand blast nozzle through an apron or other opening into the interior, there being a sight window to enable the operator to view the work. It is also common practice to have the floor of the sand blast room in the form of a grill so that the used sand may fall through the grill into a hopper therebelow.

Before used sand or other abrasive material can be delivered to a sand blast generator for reuse, dust must be removed therefrom. Heretofore, the use of a sand blast generator below the floor has been impractical because there has been no suitable method of removing dust from the abrasive material before delivery to the generator. Dust removing apparatus heretofore available has required more headroom than is available in the average basement. It has, therefore, been customary to convey the abrasive horizontally below the floor and to then elevate it to a point well above the main floor where it can be dropped into an aerator and then into a generator, both located on the main floor. This arrangement is objectionable because it consumes valuable floor space.

It is a general object of the present invention to provide a compact aerator which may be used for a variety of purposes, and which requires little head room so that it is particularly well adapted to be attached to the bottom of a hopper, below a sand blast room, to deliver cleaned abrasive by gravity into a generator also located in the basement below the aerator.

A further object of the invention is to provide an improved aerator of the class described wherein novel means is employed for subjecting a material to an efficient aerating action.

A still further object of the invention is to provide a device as above described which includes a vertically movable, hollow conical valve member, the arrangement being such that the material to be acted upon such as used abrasive falls by gravity in a thin conical sheet down the sides of the valve member, and there being an air-exhausting tube projecting into the hollow conical valve to create air currents which serve to remove dust or other matter from the falling material while permitting other portions of the material such as the heavier clean abrasive to fall by gravity into a generator or other receptacle therebelow.

2
Other objects of the invention are to provide an aerator which is relatively simple in construction, which can be adjusted to meet various conditions, which is relatively inexpensive to manufacture, efficient in operation, and well adapted for the purpose described.

With the above and other objects in view, the invention consists of the improved aerator, and all its parts and combinations, as set forth in the claim, and all equivalents thereof.

In the accompanying drawings, in which the same reference numerals designate the same parts in all of the views:

Fig. 1 is a perspective view showing the improved aerator connected to the top of a sand blast generator;

Fig. 2 is a side elevational view of the aerator alone, parts being broken away and shown in section; and

Fig. 3 is an end elevational view of the aerator, parts being broken away and shown in section.

Referring more particularly to the drawings, which indicate only one type of use for the improved aerator, the numeral 10 designates the lower portion of a hopper, the latter projecting from beneath the floor of a sand blast room to receive used abrasive material which has fallen through the grill in the floor of said sand blast room. Positioned against the bottom of the hopper 10 is a tray 11 having an opening 12 which registers with the open lower end of the hopper 10. Projecting downwardly from the opening 12 in the tray is a hopper-like bottom 13 having a discharge opening 14. An external ring 15 surrounds the discharge opening 14 and has legs 16 depending therefrom which support the ring in spaced position above the upper end of a cylinder 17. The latter projects from the top of a sand blast generator 18 and is adapted to direct cleaned abrasive into the generator. The sand blast generator may be of any standard type commonly used in sand blasting operations.

Seated against the lower face of the external ring 15 and held in position by a flanged circular retaining member 19 is a circular seal 20 of synthetic rubber or other suitable material. The circular retainer 19 may have its upper edge welded or otherwise connected to the lower face of the member 15.

Suitably journaled transversely through the hopper-like tray bottom 13 is a shaft 21. Mounted rigidly on the shaft within the hopper-like bottom 13 is an arm 22. The outer end of the arm is pivotally connected as at 23 between spaced ears 24 which project upwardly from the top of a hollow conical valve member 25.

Rigidly connected at one of its ends to a projecting end of the shaft 21 is an arm 26. The other end of the arm 26 is pivotally connected as at 27 to one end of a link 28. The link 28 is pivotally connected to a crank 29 for operating a butterfly valve 30, the latter being located in an air-exhaust conduit 31. The conduit 31 is connectable to a source of suction such as an exhaust fan.

Also rigidly connected to the shaft 21 is one end of an arm 32. The latter carries adjustable weights 33. It may also be formed with a hole 34 for the connection of a pull chain.

The exhaust conduit 31 has its inner end projecting into the cylindrical extension 17 on top of the sand blast generator, and the extreme inner end of the conduit is in the form of an elbow to provide an upwardly projecting portion 35 which has an open end in a protected position within the hollow interior of the conical valve member. Rods 36 project upwardly from the conical valve and extend slidably through holes in the ring 15. Adjustment nuts 37 are threaded on the upper ends of the rods.

In use of the invention, a chain extending upwardly from the hole 34 in the end of the arm 32 may be employed to control the action of the valve 30. By releasing the chain the weights 33 will cause the arm 32 to swing in a clockwise direction (referring to Fig. 2). This will act through partial rotation of the shaft 21, movement of the arm 26, and movement of the link 28 to open the valve 30. At the same time it will also act through the arm 22 to lower the conical valve member 25 out of sealing relationship with the annular seal 29. Sand which has been used in the sand blast room in the floor above, and which has previously collected in the hopper 10 and in the hopper-like bottom 13 of the tray 11, will fall by gravity down the sides of the conical valve member 25 in the form of a thin conical sheet. The maximum thickness of this sheet may be adjusted by use of the nuts 37. At the same time the suction created in the exhaust conduit 15 will cause air from the exterior to enter the open top of the cylinder 17, as indicated by the arrows, and cause said air to pass through the conical sheet of falling abrasive just below the bottom of the valve 25 to remove dust from the falling particles. This exhaust action will then cause the air to flow upwardly into the protected zone within the valve member 25 and then downwardly into the upper end 35 of the exhaust pipe elbow. Thus, because of the novel arrangement and the maintenance of the thin sheet of falling abrasive, dust is very effectively removed while the clean abrasive, being heavier, is unaffected by the air currents and falls into the generator below for reuse in the sand blasting apparatus.

The aerating apparatus is very compact and makes it possible to accommodate both the

aerating apparatus and the sand blast generator below the floor level so that valuable space on the main floor is not consumed. The apparatus is very simple and inexpensive and is very efficient in its operation.

The invention is suitable for a wide variety of uses, for example, grain or other granular material may be inserted in the hopper 10 and subjected to an aerating action to remove dust or other light material from the grain. In addition, the apparatus is suitable for removing dust from fine coal by causing the coal in a pulverulent state to enter the hopper 10 so that it may be aerated. It is also possible to place a liquid in the hopper so that the liquid is delivered from the sides of the cone in a thin circular sheet where it may be subjected to the action of air or other gas to remove undesired vapors or odors from the liquid. A reverse type of operation is also possible with the apparatus, that is, liquid flowing from the sides of the valve member may be employed to wash air which is circulated through the apparatus so that dust, smoke or other foreign particles will be removed from the air due by the action of the liquid thereon.

Various changes and modifications and other adaptations may be made without departing from the spirit of the invention, and all of such changes are contemplated, as may come within the scope of the claim.

What I claim is:

In an aerator, a material receptacle having a bottom opening, a conical closure and regulating valve member mounted for movement toward and away from sealing relationship with said opening with the base of the valve member located below the opening whereby when the valve is lowered material falling by gravity from said receptacle will be directed in the form of a conical sheet by the external surface of said valve member, means including an exhaust conduit for subjecting said sheet to the action of gaseous currents, a valve in said exhaust conduit, and common manually operated mechanism for controlling the opening of said exhaust conduit valve and the lowering of said conical valve simultaneously.

RICHARD RUEMELIN.
